ASH TRAY

Bern E. Wolf and James H. Lee, Los Angeles, Calif.,
assignors to Prestige Hardware Corporation, Industry,
Calif., a corporation of California

Filed May 11, 1961, Ser. No. 65,117

Term of patent 14 years

(Cl. D85—2)

FIG. 1 is a perspective view showing the ash tray of our design;

FIG. 2 is a plan view;

FIG. 3 is a side elevational view;

FIG. 4 is a front elevational view;

FIG. 5 is a rear elevational view; and
FIG. 6 is an enlarged, fragmentary section taken on the line 6-6 of FIG. 2.

We claim:

The ornamental design for an ash tray, as shown.
